VARIABLE RESISTANCE DEVICE

Newton C. Schellenger, Elkhart, Ind., assignor to
 Chicago Telephone Supply Co., Elkhart, Ind.,
 a corporation of Indiana

Application April 21, 1934, Serial No. 721,728

9 Claims. (Cl. 261—55)

This invention relates to a variable resistance device of the type in which an actuating arm moves a contactor over the resistance element and applies more particularly to variable resistance devices of the type used in volume control or tone control circuits in radios or public address systems.

It has often been found desirable to actuate other control devices, positioned in near proximity to the variable resistance device, by the same actuating means which is used to operate the variable resistance device.

I am aware of the fact that others have proposed various means for the actuation of controls arranged adjacent to a variable resistance device such as the transient operation of a switch or the actuation of a series of similar controls arranged in tandem relationship by means of a single actuating member. But in all these previously proposed devices the single actuating means is positioned, relative to the variable resistance control and the additional control so that a complete actuation of one of the controls must of necessity also actuate the other control 25 or controls. In other words, the various controls to be actuated by the single actuating means were arranged in such operative relationship to the latter that when one of the controls is actuated in its entirety the other control or controls must of necessity also be operated. In a 30 plurality of adjacent controls, all of which are to be actuated by a single actuating means, it may often be desirable to refrain from actuating one or more of the controls even though the adjacent control or controls are actuated in their entirety.

It is an object of the present invention to provide a variable resistance control device with an actuating means which at the option of the operator may be made to actuate an adjacent control device, but which need not actuate the adjacent control device even though the variable resistance device is actuated throughout its full range.

It is another object of this invention to provide a single actuating means for a plurality of control devices which actuating means is normally arranged for actuation of one or more control devices but which upon being actuated 50 in a particular manner is adapted to actuate one or more additional control devices.

It is a further object of my invention to provide an enclosed resilient element for maintaining the actuating means of a control device in a normal operating relationship with one or more

control devices and upon application of force against said resilient element the actuating means is adapted to be placed in operating relationship with one or more additional control devices.

It is a further object of my invention to provide a substantially enclosed, electrically shielding cover for a control device having a rotatable and axially movable actuating means and means integral with said cover operable as a journal bearing and thrust bearing for an actuating shaft.

It is a further object of my invention to provide a control device with a metallic cover member having stop elements for limiting the movement of the control mechanism struck therefrom at such portion of said cover member which has the greatest supporting strength for said stop elements.

A further object of my invention is to provide a control device having an actuating shaft and bearings for said shaft, positioned at extreme opposite portions of said device so as to afford the maximum support for said shaft and to prevent binding of said shaft upon slight defective alignment of the bearings.

It is a further object of my invention to provide a variable resistance device having a rotatable and axially movable actuating means and a resilient contact arm adapted to expand in unison 30 with the axial movement of said actuating means to maintain a driving engagement with said actuating means and maintain electrical contact between a resistance element and a plurality of current conducting members in all axial positions 35 of said actuating element.

It is a further object of my invention to provide a variable resistance device comprising a rotatable and axially movable shaft and a substantially enclosed metallic housing for electrically shielding said variable resistance device 40 from associated control devices.

Another object of my invention is to provide a variable resistance device housing in which parts of the housing may be fastened to each other without leaving any undesirable and unsightly parts projecting therefrom.

Still further advantages of my invention will become evident by reference to the following description taken in connection with the accompanying illustrations of one specific embodiment thereof, the scope of the invention to be limited only as defined by the appended claims.

In the drawings:

Fig. 1 is a plan view of a variable resistance

device constructed in accordance with my invention, with the top of the housing and the resilient spring member removed to show the relationship of the various parts.

5 Fig. 2 is a vertical sectional view, taken along line 2—2 of Fig. 1, and showing the shaft in its normal position spaced from the thrust bearing.

10 Fig. 3 is a vertical sectional view similar to Fig. 2 and showing the shaft forced into position against the thrust bearing.

15 Fig. 4 is a top plan view, on a slightly reduced scale, of the variable resistance device shown in Fig. 1 with the shaft shown in section adjacent the top of the housing.

18 Fig. 5 is a bottom plan view of the device shown in Fig. 1 and illustrating the means of connecting the housing to the grounding plate.

20 Fig. 6 is a vertical elevational view of the device shown in Fig. 4.

25 Fig. 7 is an exploded isometric assembly view of a variable resistance device constructed in accordance with the invention and illustrating the relationship of the various parts to each other.

30 Fig. 8 is an enlarged fragmentary view of a section of the grounding plate at an intermediate stage of manufacture.

35 Fig. 9 is a sectional view taken along the line 9—9 of Fig. 8.

40 Fig. 10 is an enlarged fragmentary view of a section of the grounding plate after the tongue has been depressed to its finished form.

45 Fig. 11 is a sectional view taken along the line 11—11 of Fig. 10.

50 Fig. 12 is a vertical sectional view of a modified form of variable resistance device constructed in accordance with the invention.

55 Referring to the drawings in which is shown one embodiment of the invention for illustrative purposes and in which like reference characters designate similar parts throughout, 20 indicates the cup-shaped control housing for the variable resistance control. The control housing 20 is provided with a circular, substantially flat end wall 24 from which extends a cylindrical side wall 27 (see Fig. 7). The free edge of the side wall is provided with a plurality of extensions 21 spaced from each other and hereinafter referred to as ears. A section 22 of the free edge 60 of the cylindrical side wall (see Figs. 3 and 7) is cut away to prevent contact with the current carrying terminals of the variable resistance device. Stop members 23 are struck from the side wall of the housing. These stop members for limiting the angle of rotation of the control mechanism must be of substantial height and are therefore struck from a section of the side wall which is spaced a substantial distance from the cut away section 22, in order to provide the necessary strength and rigidity to these stop members.

65 The central portion of the housing is provided with an annular depressed portion 25, substantially U-shaped in cross-section, the innermost portion of which consists of a cylindrical section 26 which is concentric with the cylindrical side wall 27 of the housing. The inner surface of section 26 is constructed to fit snugly about the reduced portion 37 of a shaft 36 and is adapted 70 to function as a journal bearing for said shaft. The flat inner surface 25a of the annular depressed portion 25 is adapted to function as a stop member and thrust bearing for shoulder 38 of the shaft 36.

An insulation strip 28 having narrow slots 29

is fitted snugly to the inner surface of the side wall 27 with the stop members 23 of the side wall engaging the walls of slots 29. One edge of strip 28 will abut against the end wall 24 of the housing whereas the opposite edge of the strip will abut against an insulating base plate 96.

5 The base plate 96 is provided with an integral arcuate, extended shelf section 98 and supported on the base plate is a resistance element 97. In the particular embodiment disclosed herein, the 10 resistance element is of the planar carbonaceous type although other known types of resistance element may be used equally well to fulfill the requirements of this invention. The planar, carbonaceous type, resistance element 97 may comprise a coating of carbon or graphite composition 11 on a sheet of tough, yieldable, insulating material such as parchment paper as is clearly illustrated in Figs. 1 and 2. The resistance element is provided with a break 89 between the 15 ends thereof, or may comprise a coating of suitable carbonaceous resistance material applied directly onto the base plate.

20 A substantially circular metallic grounding plate 90 is positioned directly on the rear surface 25 of the base plate. The grounding plate 90 is provided with a plurality of tongue sections 93 spaced from each other on the outer marginal periphery thereof. The tongue sections are flattened so as to produce depressed offset portions 30 on the outer surface of the grounding plate. These offset tongue portions 93 are produced by cutting sections from the outer periphery of the grounding plate thereby leaving a plurality of pairs of parallel sided notches 83, 84 and a tongue 35 flange 70a being forced into the surface of the base plate, as is clearly shown in Fig. 2. The edge of shoulder 75 is then peened over or spread out to bear against the outer surface of the grounding plate and thereby securely fasten the base plate and grounding plate together.

The housing 20 is securely fastened to the grounding plate by bending the ears 21 thereof over onto the depressed tongues 93 of the grounding plate thereby forcing the base plate firmly against the insulation strip 28. The ears 21 are adapted to be retained within the said depressed tongue portions 93 of the grounding plate, thereby providing a smooth even outer surface on the said plate 90. This even outer surface will permit connection of the variable resistance device to a panel or other plane surface without distortion of the grounding plate or base plate when it is drawn up tightly against the panel 107 by screwing a nut 109 onto the threaded portion 72 of the bushing projecting through an opening 110 of the panel.

The bushing 70 has a longitudinal bore through the center thereof. The greater part of the length of said bore is preferably of a diameter considerably larger than the external diameter of the shaft 36 so as to provide a very loose fit with the shaft 36. The end of the bushing extending from the variable resistance device contains a comparatively short bored section 73 of a diameter very slightly larger than the external diameter of the shaft 36 so as to constitute a journal bearing for the shaft. The shaft extends through and has a portion thereof projecting from the bushing to constitute a handle for imparting axial or rotatable movement to said shaft.

When the two journal bearings 26, 73 for the shaft are positioned at extreme opposite sides of the variable resistance device as disclosed in the preferred embodiment of the invention, a much greater rigidity and stability is imparted to the shaft than would be possible if the bearings were positioned closer together. Furthermore, the exact alignment of bearings is not as critical and the allowable tolerances need not be so close when the bearings are comparatively short and are spaced a substantial distance from each other as would be the case if the bearings were long or spaced close together.

The arcuate extended shelf section 98 of the base plate 96 contains a plurality of parallel sided notches 104, 105 and 106 (see Figs. 3 and 5) in which are positioned a plurality of current carrying terminals 79, 79, and 85. The grounding plate which overlies the base plate has the section 92 thereof removed to prevent making contact with these terminals. The end terminals 79, 79 are positioned into notches 104 and 106 and are adapted to contact the ends of the resistance element, as shown at 82 in Fig. 7, whereas the central terminal 85 is positioned in notch 105 and is adapted to be connected through other elements with the contactor shoe, as will be hereinafter described. For a detailed description of the particular manner of connecting the terminals to a resistance device of this type, reference is made to my co-pending application Serial No. 711,644, filed February 17, 1934.

As pointed out above, the actuating shaft 36 is reduced in diameter adjacent the end wall 24 of the housing, the reduced section 37 of the shaft extending through and projecting from the said end wall 24. A drive arm 39 is fixed

to the main portion of shaft 36 adjacent the reduced portion thereof.

The drive arm 39 comprises a flat plate having an integral cylindrical collar portion 40 formed therein, the collar portion 40 being arranged perpendicular to the flat surface of the plate and may be formed by drawing the same from the metal of the flat plate. One end of the plate terminates in a downwardly directed finger 41 and the other end of the plate terminates in a blunt section having oppositely directed sides 44, 45. A second downwardly directed finger 42 is formed on the arm intermediate the collar 40 and the sides 44, 45. This finger 42 is preferably spaced from the collar 40 a distance equal to that between finger 41 and the collar 40. In order to construct the finger 42 according to exact dimensional requirements by a punching operation, it is preferable that a section of the metal surrounding the finger be first removed to leave a finger of the exact desired dimensions which may then be bent downwardly to the position shown in Fig. 7 of the drawings. The inner surface of the collar 40 is knurled or otherwise provided with axially extending teeth 46 (see Fig. 2) which are adapted to be forced into the metal of the shaft 36 when the arm is forced thereon, and thereby dispenses with the necessity of fastening elements such as set screws or key members between the shaft 36 and arm. If desired, similar teeth 46a may be provided on the shaft for coengagement or to mesh with the teeth 46 of the drive arm.

The fingers 41 and 42 of the drive arm are adapted to fit into notches 49 and 48 respectively of a motion-transmitting plate. This motion-transmitting plate is made of insulating material and has an opening 52 into which the shaft 36 is positioned and thus permitting the fingers of the drive arm to engage the sides of the notches 49 and 48. The plate 47 is considerably wider than the drive arm 39 as is clearly shown in Fig. 1, and at least one end of this plate is arranged to substantially overlie the converging ends of the resilient contact arm members 58, 58 to prevent dislodging of the contact shoe in case of violent vibration. For simplicity in assembly, both ends of the plate are constructed alike. The plate 47 is further provided, on opposite sides thereof, with notches 50 and 51 for engagement with upstanding projections 54, 54 of a contactor arm 53 and thereby transmit motion from the drive arm 39 to the contactor arm 53.

The contactor arm 53 is composed of resilient metallic material having a substantially circular slip ring portion with an opening 56 therein which is sufficiently large that the shaft 36 may extend therethrough without contacting the sides of the opening. A pair of comparatively long converging arms 58, 58 extend from the slip ring portion and are joined at their converging ends. Extending from the junction of the converging ends is a downwardly directed toe 57 which is adapted to project into an opening 61 of the contact shoe 60. The contact shoe 60 is constantly maintained in contact with the resistance element 77, and is pressed against the resistance element by the resilient contactor arm 53. The upstanding projections 54, 54 are adapted to prevent contact of the contactor arm with the shaft 36 by their engagement with the notches 50, 51 of the motion-transmitting plate. The projections 54, 54 are prevented from making contact with the drive arm 39 due to the fact that the plate 47 is wider than arm 39. The contactor arm is 75

bent, warped or dished so as to function as a spring member. When the shaft is moved axially the resilient contactor arm 53 is adapted to maintain a contact between the contact shoe 60 and the resistance element 77 as will be more particularly described below.

A collector ring 62 is positioned directly below the body portion of the contactor arm 53 and is constructed to substantially the same size as the slip ring portion of the contactor arm so as to be constantly maintained in contact therewith. An extending arm 65 is provided on the collector ring (see Fig. 3) which terminates in a narrow finger portion 66. This finger portion 66 is adapted to be projected through a small opening 87 in the end 86 of the central terminal 85. The end 86 of the terminal is then bent over onto the base plate thereby clinching the end 86 and the finger 66 securely together. Care must be taken to prevent contact between the resistance element and the bent over end 86 of the terminal. This may be done, as shown in Fig. 7, by cutting out a section 76 of the resistance element. The collector ring 62 is provided with a large opening 67 of substantially the same size as opening 56 of the contactor arm, and also with guide projections 63, 64 to prevent contact of the collector ring with the shaft 36. An insulating washer 68 is positioned between the collector ring 62 and the circular bushing 70 for the purpose of preventing contact between the collector ring and bushing. The washer 63 is slightly larger in diameter than the flange 70a of the bushing so that the downwardly directed guide projections 63 and 64 of the collector ring will be prevented from contacting the flange 70a. The guide projections 63, 64 engage diametrically opposite portions of the insulating washer 68 to thereby prevent contact of any portion of the collector ring with the shaft 36.

A dished spring member 31 having a plurality of outwardly directed arms 32 and a centrally positioned opening 33 for the shaft 36 is positioned between the drive arm 39 and the end wall 24 of the housing to normally maintain the shaft in the position shown by Fig. 2, with the drive arm, motion-transmitting plate, contactor arm, collector ring and insulating washer all forced into close contact with each other and against the flange 70a of the circular bushing. A washer 34 preferably formed of insulating material, may, if desired, be positioned between the spring 31 and the drive arm 39. The washer 34 is provided with a centrally positioned opening 35 sufficiently large to snugly fit about the collar 40 of the drive arm.

An actuating arm 100 may be mounted on the reduced end 37 of the shaft which projects from the end wall of the housing. This arm 100 can be fixed to the reduced end of the shaft in any desired manner, for example, by a set screw 102 positioned in the arm. The arm 100 is further provided with a means such as an eccentrically mounted projection 101 for actuating an element 103 of an adjacent control device. As will be noted by reference to Figs. 2 and 3, the element 103 of the adjacent control cannot be actuated when the shaft is in its normal position as shown in Fig. 2. In order to actuate the adjacent control device the shaft 36 must be moved axially against the action of spring 31, that is, before the eccentrically mounted projection 101 can engage the element 103 of the adjacent control, the shaft must be moved axially to the position shown in Fig. 3.

It will be obvious that many other means of driving engagement of the reduced end of the shaft with an adjacent control device, for operation of the control device when the shaft is in its advanced axial position, may be devised by anyone skilled in the art and the specific embodiment herein disclosed is for illustrative purposes only and the invention is not to be limited thereby.

When the shaft is moved axially against the action of spring 31, as shown in Fig. 3, the shoulder 38 of the shaft is adapted to contact the surface 25a of the thrust bearing, the surface 25a functioning both as a means for limiting the axial movement of the shaft as well as providing a surface against which the shoulder 38 may turn. It will be furthermore readily apparent that when the shaft is forced against the thrust bearing the resilient contactor arm will assume its natural bent or dished shape so as to maintain a contact with the collector ring as well as maintaining a pressure on the contact shoe to preserve an electrical contact between the latter and the resistance element.

As has been pointed out above the stop members 23, 23 are struck from the side wall of housing 20 at a substantial distance from the portion 22 of the side wall which is removed to prevent contact with the terminals. The stop members 23, 23 are positioned to be engaged by ears 44, 45 of the drive arm 39 when the contact shoe is adjacent an end of the resistance element. Inasmuch as the drive arm will be moved axially with the shaft, the stop members 23 must be of considerable height to insure engagement at all times with the ears 44, 45 of the drive arm 39 and it is primarily for this reason that the members 23 are struck from the housing at a distance from the cut-out section 22.

In this connection it will be noted that the rotational movement of the shaft and associated elements is limited by direct impact of the drive arm against the stop members. The drive arm is directly connected to the shaft in a very rigid manner, consequently there is much less danger of damaging the control device by the shock of the impact with the stop members than if some other element of the device were used as a means for limiting the rotational movement.

In the operation of the variable resistance device herein disclosed, when used as a simple rheostat, the current is adapted to pass from an end terminal to the resistance element, then to the contact shoe, then to the contactor arm, from the contactor arm to the collector ring and from the collector ring to the central terminal. When the shaft is in its normal retracted position shown in Fig. 2, rotation of the shaft will actuate only the variable resistance device. If the shaft is rotated in a clockwise direction, the side 45 of the drive arm will eventually abut against one of the stop members 23, 23 at which position the contact shoe will be adjacent one end of the resistance element. Upon rotation in the other direction the side 44 of the drive arm will abut against the other stop member and the contact shoe will be positioned adjacent the other end of the resistance element. It is preferable that the contact shoe can be moved on the resistance element adjacent portions 82, 82 of the terminals 70 without making a contact with the same, as any direct contact between the end terminals and the shoe is undesirable.

The contact shoe is moved over the resistance element by means of the contactor arm 53. The

contactor arm is rotated by the motion-transmitting plate 41 which in turn is rotated by the drive arm 39. The drive arm 39, being fixedly mounted on the shaft 36 will be rotated therewith. Rotation of the shaft in its axially advanced position, with the shoulder of the shaft resting against the thrust bearing 25, will actuate both the variable resistance device as well as any additional device which may be positioned for engagement 10 with the axially advanced shaft or with actuating means fixed to said shaft.

In order to provide the necessary strength and rigidity to the entire device and to eliminate a binding of the axially and rotatably movable shaft because of slight inaccuracies in the manufacture of the various parts, the journal bearings for the shaft are spaced from each other as far as possible in opposite extreme positions of the housing and bushing. Thrust bearing means are 20 provided in the housing adjacent the journal bearing, to function as an impact absorbing means, and to aid in withstanding the endwise rotational thrust of the shaft.

In the modified form of variable resistance device shown in Fig. 12, the shaft 36' is mounted in the housing 20' and its associated bushing 70' for rotational movement only and illustrates the manner in which the control device may be constructed in a narrow compact unit when the axial movement of the shaft can be dispensed with. This modified construction retains the advantages of the other features of the invention to provide an exceptionally rugged, uniformly and smoothly operating unit, which can be constructed very economically and without the usual critical requirements of variable resistance devices known heretofore that each individual element be maintained within severely fine tolerances.

The shaft 36' is supported by the widely separated comparatively short journal bearings 26' of the housing 20' and 73' of the bushing 70'. As in the case of the variable resistance device shown in Figs. 2 and 3, this feature will permit smooth, uniform rotation of the shaft even though there is a slight malalignment between the two bearings. The shoulder 38' of the shaft will be continuously maintained in direct contact with the thrust bearing 25', thus permitting a considerable narrowing of the side wall of the housing. If an exceptionally smooth operation is desired, a small, smooth thrust washer 105' may be positioned between the shoulder 38' and the thrust bearing 25'. When no additional control is positioned adjacent the variable resistance device for actuation by the shaft 36' the reduced end of the shaft 37' may be cut off evenly with the end wall 24' of the housing 20' as shown in Fig. 12. Nevertheless, it will be obvious that the reduced end of the shaft may be extended beyond 60 the end wall 24' for the positive actuation of an adjacent control in a known manner. It is not necessary that the stop member 23' be made as long as stop member 23 by reason of the fact that the drive arm 39' is not moved axially as is 65 drive arm 39 in the modification described above, nevertheless it is preferably struck from a portion of the housing spaced from the terminals to prevent cutting through the free end of the side wall of the housing as would be the case if 70 it were struck from the section of the housing adjacent the terminals.

The grounding plate 90' is provided with depressed tongues 93' corresponding to the depressed tongues 93 as previously described, and the ears 21' of the housing are bent over onto

the tongues 93' so as to prevent troublesome projections on the external free surface of the grounding plate 90'.

The various other parts of this modified construction of variable resistance device are constructed and assembled in the same manner and relationship as above described with references to Figs. 1-11.

It is to be understood that the specific embodiment of the invention illustrated and described may be varied in many details of its construction within wide limits without departing from the spirit of the invention, and that the invention is to be limited only within the terms of the appended claims.

I claim:

1. A variable resistance control device having in combination, a housing, a shaft rotatably mounted in said housing, a journal bearing in one side of said housing, a bushing extending 20 from the opposite end of the housing, a narrow journal bearing in the outer end of the bushing, said journal bearings being positioned at extreme opposite ends of said housing, whereby maximum rigidity with minimum bearing surfaces may be obtained between said shaft and bearing in the bushing and the bearing in the housing.

2. A variable resistance device having in combination, a metallic open-ended housing member, a metallic plate overlying the open end of said housing member, said metallic plate being formed with a plurality of peripherally arranged tongues depressed below the plane of the exterior face of said plate, a plurality of ears integral with said housing member, said housing and plate being secured to each other by bending said ears over onto said depressed tongues, and an actuating shaft extending through said plate and housing.

3. A variable resistance device having in combination, a metallic open-ended housing, a plurality of ears extending from the open end of said housing, a metallic plate adapted to close the open end of said housing, a plurality of 45 tongues at the marginal periphery of said plate, said tongues being depressed below the plane of the exterior surface of said plate, said housing and plate connected to each other by bending of said ears over onto said depressed tongues where- 50 by an even exterior surface is provided on said plate.

4. A variable resistance control device having in combination, a housing having a perforation therethrough and an annular depressed portion 55 immediately surrounding said perforation, a resistance element in said housing, contacting means cooperating with said resistance element, means for actuating said contacting means including a rotatable shaft extending into said 60 housing, said annular depressed portion constituting a combined journal and thrust bearing for said shaft.

5. A variable resistance device having in combination, a cup-shaped metallic housing having a 65 cylindrical wall, a variable resistance in said housing, a rotatable contact driving member in said housing, lugs struck inwardly from the wall of said housing, a strip of insulating material against the inner surface of the cylindrical wall of the 70 housing, the lugs extending through the insulating material to position the same, the insulating material covering the openings in the housing wall from which the lugs are struck, and portions on the rotatable contact driving member adapted 75

- to engage the lugs to limit rotation of said member.
6. A variable resistance device having in combination, a housing, a resistance in said housing, a shaft extending through at least one wall of said housing, a contactor engaging the resistance and moved by rotation of the shaft, means carried by the shaft and rotatable therewith connected to the contact, said means engaging a fixed connector carried against the inner face of one wall of the housing, and resilient means engaging the opposite inner wall of the housing to urge said first means against the fixed connector and toward the first wall.
- 15 7. A variable resistance device having in combination, a housing, a resistance in said housing, a shaft extending through at least one wall of said housing, a contactor engaging the resistance and moved by rotation of the shaft, conducting means connected to the contact and carried by and rotatable with the shaft, a second conducting means carried by an inner wall of the housing, and resilient means engaging the opposite inner wall of the housing and urging the shaft toward 25 the first-named wall to cause contact between the said conducting means.
8. A multiple circuit control device comprising a variable resistance having in combination, a housing, a shaft rotatably mounted in and extending through said housing, a resistance strip in the housing, a contactor engaging the resistance strip and rotated by the shaft, a shoulder on said shaft, a bearing surface integral with said housing for a circumferential surface of said 35 shaft, a second bearing surface integral with said
- housing for an end surface of the shoulder on said shaft, stop means limiting movement of the shaft in the direction away from the second bearing, the contactor being maintained in engagement with the resistance strip throughout axial movement of the shaft, means for yieldingly maintaining the shoulder spaced from the second bearing, actuating means on the end of the shaft beyond the second bearing, and a second control device located to be actuated by said means when the shaft is in engagement with the second bearing.
9. A multiple circuit control device comprising a variable resistance having in combination, a housing, a shaft rotatably mounted in and extending through said housing, a resistance strip in the housing, a contactor engaging the resistance strip and rotated by the shaft, a shoulder on said shaft, a journal bearing formed integrally with said housing at one end thereof, a second journal bearing at the opposite end of said housing, a thrust bearing formed in the wall of said housing adjacent said first-named journal bearing within the housing, stop means limiting movement of the shaft in the direction away from the thrust bearing, the contactor being maintained in engagement with the resistance strip throughout axial movement of the shaft, means for yieldingly maintaining the shoulder spaced from the thrust bearing and against said stop means, actuating means on the end of the shaft beyond the second bearing, and a second control device located to be actuated by said means when the shaft is in engagement with the thrust bearing.

NEWTON C. SCHELLENGER.

CERTIFICATE OF CORRECTION.

Patent No. 2,145,953.

February 7, 1939.

NEWTON C. SCHELLENGER.

It is hereby certified that error appears in the printed specification of the above numbered patent requiring correction as follows: Page 5, second column, line 23, claim 1, for "bearings" read bearing; lines 27 and 28, strike out the words "in the bushing and the bearing in the housing" and insert the same before "being" in line 23, same claim 1; and that the said Letters Patent should be read with this correction therein that the same may conform to the record of the case in the Patent Office.

Signed and sealed this 11th day of April, A. D. 1939.

Henry Van Arsdale
